UNITED STATES PATENT OFFICE

143,615

DESIGN FOR A HUMIDOR OR SIMILAR ARTICLE

George E. Nettleton, Jr., Hollywood, Calif., assignor to Lockheed Aircraft Corporation, Burbank, Calif.

Application August 9, 1945, Serial No. 121,339

Term of patent 7 years

(CL. D85—2)

To all whom it may concern:

Be it known that I, George E. Nettleton, Jr., a citizen of the United States, residing at Hollywood, in the county of Los Angeles and State of California, have invented a new, original, and ornamental Design for a Humidor or Similar Article, of which the following is a specification, reference being had to the accompanying drawings, forming a part thereof:

Figure 1 of the drawings is a front perspective view of a humidor or similar article embodying the new design as it appears from a point above and slightly to one side of the humidor;

Figure 2 is a reduced side elevational view of the humidor appearing in Figure 1;

Figure 3 is a front elevational view thereof; and

Figure 4 is a top plan view of the base portion of the humidor being a view taken as indicated by line 4—4 on Figure 3.

I claim:

The ornamental design for a humidor or similar article, substantially as shown.

GEORGE E. NETTLETON, JR.
